COMPOUND REGENERATIVE COKE OVEN

Friedrich Totzek, Essen, Stoppenberg, Germany,
assignor, by mesne assignments, to The Kop-
pers Company of Delaware, Pittsburgh, Pa., a
corporation of Delaware

Application September 24, 1930, Serial No.
484,158. In Germany September 27, 1929

11 Claims. (Cl. 202—144)

This invention relates to improvements in coke ovens particularly of the type known as the Koppers oven.

Compound regenerative coke ovens with draft direction changers and hairpin or inverted U heating flues are well known. Such ovens include regenerators arranged under the base of the retort chambers extending longitudinally with respect thereto, and a transverse central partition wall dividing the oven in half in such manner that all of the regenerators under one half of the oven preheat gas and air while the regenerators under the other half are being traversed by the waste heat. It has furthermore already been proposed to directly connect the regenerators on one side of the partition wall with the flues immediately thereabove and with the flues above the other side of the partition wall by means of base or bottom flues.

The present invention relates to a special form of this oven system wherein, in particular, the scissors-like crossing of base flues which extend from regenerators whose ends abut against one another is replaced by base flues which extend, not from every regenerator but from every other regenerator. This is accomplished by dividing every even number regenerator in one half of the oven and every odd regenerator in the other half of the oven into two sections by means of a partition wall extending centrally in the direction of the chamber, and by connecting only the undivided regenerators with the base flues on the other half of the oven.

With the above arrangement in one half of the oven every even number undivided regenerator serves to preheat the gas and every odd number undivided regenerator serves to preheat the air. The half of each subdivided regenerator lying next to each even number undivided regenerator supplies air while the other half of the subdivided regenerator lying next to each odd number regenerator supplies gas. While the above mentioned portion of the oven is serving as stated, all the regenerators in the other half of the oven are storing up waste heat developed by the burning of the preheated gas and air in the hairpin flues.

Every undivided regenerator is connected with hairpin flues on both sides of the central wall. The communication with the flues thereabove is direct whereas the communication with the flues above the other half is through the base flues which in turn have branches situated in the hearth leading to the hairpin flues on each side. The subdivided regenerators are connected only

with the corresponding hairpin flues of the half of the oven lying directly above the same.

Other features of novelty will be apparent from the following specification when read in connection with the accompanying drawings in which one embodiment is illustrated by way of example.

In the drawings:

Figure 1 is a vertical cross section of a portion of the oven taken on line 1—1 of Fig. 2; 65

Figure 2 is a vertical longitudinal section of the whole oven taken on line 2—2 of Fig. 1;

Figure 3 is a horizontal section taken on line 3—3 of Fig. 1;

Figure 4 is a vertical section on the line 4—4 70 of Figure 2; and

Figure 5 is a horizontal section taken substantially on the line 5—5 of Figure 4.

Referring to the drawings in detail, the oven comprises a structure providing retort chambers 75 10, hairpin or inverted U flues 11 and regenerators 13, 14 and 15. The regenerators 13 and 14 separated by walls 16 are herein referred to as "subdivided regenerators", and the regenerators 15 as "undivided regenerators". The regenerators extend only half the length of the oven to a transverse partition wall 17. The undivided regenerators 15 and the subdivided regenerators 13, 14 are alternately arranged in the oven as shown in Fig. 1. The undivided regenerators on one side of the wall lie opposite the subdivided regenerators on the other half of the oven, as shown in Figure 3.

The ports or passages 18 serve to introduce air or gas in one cycle of operation and as outlets for waste gases in the other cycles. 90

The regenerators 13 and 14 communicate only with the flues 11 almost directly above through the passages 19 and 20. The undivided regenerators communicate both with the flues 11 almost directly above through passages 21 and 22 and also with the flues 11 above the other side of the wall 17 through base flues 23. The base flues have branches 25 and 26 leading to the right and to the left each branch communicating 100 with two hairpin flues 11 by means of branches 27 and 28.

To illustrate the operation of the oven, Fig. 1 has been marked to illustrate the cycle in which the gas and air are introduced, G denoting the 105 presence of gas, and A, the presence of air. These regenerators have been preheated in the previous cycle and are herein referred to as the "pre-heating half" of the oven whereas the other end is referred to as the "heat storing half". 110

Gas is introduced into the preheating half through inlets 18 into regenerators 14 G and 15 G from whence it passes through passages 20 and 22, respectively, to hairpin flues 11 thereabove. 5 Air is introduced into regenerator 15 A and 13 A and passes through passages 21 and 19, respectively, to flues thereabove where combustion occurs. The gases of combustion pass over the walls 24 of the hairpin flues and out through 10 branch flues 27 and 28 to branch flues 25 to base flues 23 to regenerators 15 in the heat storing half where residual heat is given up prior to its exit through 18 from the oven.

A portion of the air from regenerator 15 A passes into base flue 23 of the heat storing half and from there flows into branches 25, to passages 27 and 28 into hairpin flues 11 in that half. A portion of the gas from regenerator 15 G passes into base flue 23 of the heat storing half into 20 branch passages 25 to 27, and to 28 into flues 11 where combustion with the introduced air occurs. These combustion gases pass over the walls 24 and downwardly through passages 19, 20, 21 and 22 into regenerators 13, 14 and 15 and out 25 through passages 18 all in the heat storing half of the oven.

From the above description it can be readily seen that the resistance to flow of gases is uniform throughout the oven, since all the gases 30 pass through the same number of channels, though the arrangement is such that half of the gases pass through the base flues first and the remaining gases pass through the base flues, last.

Having thus described the invention, what is 35 claimed as new and desired to be secured by Letters Patent is:

1. In a battery of regenerative coke ovens comprising a series of alternate horizontal coking chambers and heating walls therefor arranged 40 side-by-side in a row, each of said heating walls including a row of hairpin combustion flues; two parallel rows of regenerators below the coking chambers and heating walls, each of the rows of regenerators extending along the battery and 45 each of said heating walls extending across the two rows of regenerators with part of the row of hairpin flues in each heating wall above each of the rows of regenerators, a central partition wall separating said two rows of regenerators centrally 50 of the heating walls; the improvement comprising the provision in each row of regenerators of regenerators of two different widths, alternate wide regenerators and intermediate narrow regenerators with two narrow regenerators adjacent to each other and intermediate each two consecutive wide regenerators, and with each two narrow regenerators that are adjacent to each other in each 55 of the two parallel rows of regenerators opposite a wide regenerator in the other row, base flues 60 on each side of said central partition wall between the level of the tops of the narrow regenerators and the level of the bottoms of the coking chambers and heating walls and communicably connecting the wide regenerators on the other side of the said partition wall with the hairpin flues in the portions of the battery above the base flues, and each of said narrow regenerators being 65 communicably connected only to hairpin flues on the same side of said central partition wall as the narrow regenerator.

2. A regenerative coke oven battery according to claim 1 wherein each of the base flues is communicatively connected to hairpin flues of each of four of the heating walls.

3. In a battery of regenerative coke ovens com-

prising a series of alternate horizontal coking chambers and heating walls therefor arranged side-by-side in a row, each of said heating walls including a row of hairpin combustion flues; two parallel rows of regenerators below the coking chambers and heating walls, each of the rows of regenerators extending along the battery and each of said heating walls extending across the two rows of regenerators with part of the row of hairpin flues in each heating wall above each of the rows of regenerators, a central partition wall separating said two rows of regenerators centrally of the heating walls; the improvement comprising the provision in each row of regenerators of regenerators of two different widths, alternate wide regenerators and intermediate narrow regenerators with two narrow regenerators adjacent to each other in each of the two parallel rows of regenerators opposite a wide regenerator in the other row, base flues on each side of said central partition wall between the level of the tops of the narrow regenerators and the level of the bottoms of the coking chambers and heating walls and communicably connecting the wide regenerators on the other side of the said partition wall with the hairpin flues in the portions of the battery above the base flues, ducts communicably connecting each of the wide regenerators with hairpin flues in the portion of at least one of the heating walls on the same side of the central partition wall as the wide regenerator, and each of said narrow regenerators being communicably connected only to hairpin flues on the same side of said central partition wall as the narrow regenerator.

4. A regenerative coke oven battery according to claim 3 in which the communicable connections of the wide regenerators and the communicating connections of one of the narrow regenerators terminate in the same limb of at least one of the hairpin flues whereby one of said connections may supply gas and the other, air.

5. A regenerative coke oven battery according to claim 3 in which passages are provided whereby each base flue is connected to hairpin flues of each of four of the heating walls.

6. A regenerative coke oven battery as claimed in claim 3 and in which the two rows of regenerators are operable in alternation with each other for concurrent inflow preheating of combustion media and outflow of waste gas, and in which every other wide regenerator in each of said two rows is for gas and the others of the wide regenerators in each of the two rows are for air.

7. A regenerative coke oven battery as claimed in claim 3 and in which the two rows of regenerators are operable in alternation with each other for concurrent inflow preheating of combustion media and outflow of waste gas, and in which every other wide regenerator in each of said two rows is for gas and the others of the wide regenerators in each of the two rows are for air, and in which in each row of regenerators the two narrow regenerators between each two wide regenerators are for gas and air with the narrow regenerator for gas next to a wide air regenerator and the narrow regenerator for air next to the wide gas regenerator so as to flank each wide gas regenerator with narrow air regenerators and to flank each wide air regenerator with narrow gas regenerators.

8. In a coke oven battery of the type comprising a series of alternate horizontal coking chambers and heating walls therefor arranged side by side in a row, each of said heating walls including a row of hairpin combustion flues, the combination with two rows of regenerators below the coking chambers and heating walls, each of the rows of regenerators extending along the battery, a first group of regenerators in each row communicating with the hairpin combustion flues located thereover, of base flues for conducting gases from the hairpin combustion flues located over each row of regenerators to a second group of regenerators in the other row, and communicating passages between the second group of regenerators in each row and the hairpin combustion flues thereover. 80
9. In a coke oven battery of the type comprising a series of alternate horizontal coking chambers and heating walls therefor arranged side by side in a row, each of said heating walls including a row of hairpin combustion flues, the combination with two rows of regenerators below the coking chambers and heating walls, each of the rows of regenerators extending along the battery, the regenerators in each row being allocated to a first group and a second group, regenerators in the second group in each row being arranged in spaced relation with regenerators in the first group located therebetween, the regenerators in the first group communicating with hairpin combustion flues located thereover only, of base flues for conducting gases from the hairpin combustion flues located over each row of regenerators to regenerators in the second group of the other row, and communicating passages between the second group of regenerators in each row and the hairpin combustion flues thereover. 85
10. The combination recited in claim 9 in which the regenerators in the first group in each row are located opposite the regenerators in the second group in the other row. 90
11. The combination recited in claim 9 in which two regenerators in the first group in each row are contiguous to each other and located between two regenerators in the second group in the same row, the two regenerators in the second group being contiguous to the two regenerators in the first group respectively. 95
